UNITED STATES PATENT OFFICE.

JAMES CADDELL, OF OAKLAND, CALIFORNIA,

ROCKING CHAIR.

Application filed September 30, 1922. Serial No. 591,632.

To all whom it may concern:

Be it known that I, JAMES CADDELL, a citizen of the United States, residing at Oakland, in the county of Alameda, in the State of California, have invented new and useful Improvements in Rocking Chairs, of which the following is a specification.

This invention relates to improvements 10 in rocking chairs.

The principal objects are to provide a rocking chair which will not cause wear of the floor or carpet or injury to baseboards or trim, which requires no greater floor 15 space than a straight chair having substantially the same seat dimensions, and which is appreciably more comfortable in use than rocking chairs of ordinary construction.

Further objects are to provide a rocking 20 chair which, in addition to serving the advantages stated, may be economically produced, will be strong and durable, and may be readily knocked down for shipment or storage and as readily assembled for use.

25 With the above objects in view the invention consists generally in novel features of structure and combination appertaining to the seat with the runners attached thereto and the stationary frame with the resiliently 30 acting yieldable supporting elements for engagement by and co-operation with said runners, all to be set forth in detail as the description proceeds.

In the accompanying drawing:

35 Figure 1 is a perspective view of a chair in which the features of the invention are incorporated.

Figure 2 is a fragmentary side elevation showing one of the runners and the yieldable supporting element therefor.

40 Figure 3 is a section on the line 3—3 of Fig. 2.

Figure 4 is a detail sectional view showing co-operating seat supporting elements 45 at the rear of the chair.

The chair seat 1 may be of any desired form, as shown being provided with a back 2 and arms 3, and is supported by a stationary frame or stand 4 which includes 50 four legs 5 and connecting rounds or braces 6.

The seat 1 is mounted to rock relatively to the frame 4 and for this purpose is provided with longitudinal runners 7 which 55 project downward from the under face of the seat and are arranged at each side

thereof. Each runner 7 has a bearing portion 8 of suitable extent which is arranged between attachment arms 9, these being secured to the seat 1 in any suitable manner, for example by screws 10. The runners 7 engage and operate upon supporting elements 11 carried by the frame 4 and which are preferably yieldable. As shown and preferred the elements 11 consist of 60 longitudinally arranged helical springs which are suspended between the upper ends of the legs 5 at the sides of the chair. The bearing portions 8 are preferably of slightly curved outline, engaging the springs 70 11 with their convex sides and are secured to said springs by centrally located clips 12 of suitable construction, which clips, however, do not interfere with the rocking 75 action of the runners.

According to the invention, provision is made for limiting the forward and rearward movement of the seat 1 and for holding said seat in a normal position located centrally between the limits of its movement, the means for this purpose acting with resilient effect and preventing too free a movement of the runners on the springs 80 11. As shown and preferred such means consists of a transverse spring 13, similar 85 to the springs 11, which is suspended between the upper ends of adjacent legs 5, for example the rear legs, and a vertical connecting member 14 which is secured at its lower end to the spring 13, centrally 90 thereof, and at its upper end to the seat 1. In the present embodiment the member 14 places the spring 13 under tension in consequence of the movement of the seat 1 in either direction and is, therefore, made rigid, 95 its lower end being formed with a suitable clip 15 by which it is attached to the spring 13 and its upper end being formed with a lug 16 by which it is attached to the seat 1.

In the use of the chair, the seat is rocked back and forth, the runners bearing on the springs 11. The movement of the runners in either direction flexes said springs and places them under tension so that good cushioning effects are produced, both vertically and in the direction of movement of the runners. At the same time the spring 13 is placed under tension by the member 14, being flexed downward when the seat is rocked backward and upward when the seat is rocked forward, the degree of tension increasing with the extent of the rock- 100 105 110

ing movement. The spring 13 acts with resilient effect gradually to limit the forward or rearward movement of the seat and to prevent it from having too free a rocking action on the supporting spring 11.

The chair may be readily knocked down by removing the screws which secure the runners 7 and the member 14 to the seat and at such time said runners and the member 14 may be folded against the adjacent rounds and the chair may be compactly arranged for shipment or storage.

It will be understood that modifications may be resorted to within the scope of the 15 appended claims.

Having fully described my invention, I claim:

1. A rocking chair comprising a frame, a seat, longitudinally arranged runners on the 20 underside of the seat and each having a longitudinally rounded underside, and yieldable longitudinal supporting elements suspended on said frame and engaged by the rounded undersides of said runners and each 25 runner being connected only at its center with the respective yielding element so as to permit rocking engagement of said runner therewith.

2. A rocking chair comprising a frame, 30 a seat, longitudinally arranged runners on the underside of the seat and each having a longitudinally rounded underside, and longitudinally arranged helical spring sup-

ports which are suspended on said frame and upon which the rounded undersides of 35 said runners are supported, each runner being only connected at its center with the respective spring, thereby permitting rocking engagement of each runner on the same.

3. In a rocking chair, in combination, a 40 frame, a seat, longitudinally arranged runners carried by and below the seat and each having a longitudinally rounded underside, yieldable longitudinal supporting elements suspended by said frame and upon which the rounded undersides of said runners have 45 rocking engagement, a transversely arranged yieldable element suspended by said frame, and a member connecting said transverse yieldable element and said seat and causing said element to yield consequent to that rocking movement of said seat.

4. In a rocking chair, in combination, a 50 frame, a seat, longitudinally arranged runners carried by and below the seat and each having a longitudinally rounded underside, longitudinally arranged helical spring supports suspended by said frame and upon 55 which the rounded undersides of said runners have rocking engagement, a transversely arranged helical spring suspended by said frame, and a member connecting said transverse spring and said seat and causing said spring to yield consequent to the rocking movement of said seat.

JAMES CADDELL.
